United States Patent Office.

SAMUEL HOKE, OF MOUNT PLEASANT, MARYLAND.

Letters Patent No. 83,282, dated October 20, 1868.

IMPROVEMENT IN CHIMNEYS.

The Schedule referred to in these Letters Patent and making part of the same.

To all whom it may concern:

Be it known that I, SAMUEL HOKE, of Mount Pleasant township, Frederick county, and State of Maryland, have invented an "Improvement in Chimneys—Self-Cleaner;" and I hereby declare the following to be an exact description thereof, reference being had to the accompanying drawings, and to the letters of reference marked thereon, making a part of this specification, in which—

Figure 1 represents a perspective view of the chimney.

Figure 2 represents a vertical section of the same.

Figure 3 represents a section of the wire cleaner, as connected with another section, at each joint of the chimney.

Figure 4 represents a cross-beam at each joint of the chimney, with a centre aperture, as a guide for the central rod or pivot of each section of the cleaner.

Figure 5 is an under-side view of the chimney.

Figure 6 represents the movable radiator, located above the fire-place.

The nature of my invention consists in the construction of an iron chimney, with a self-acting cleaner, operated by means of the vane at top, the cleaner being formed of stout wire, and supported by cross-pieces as guides, with central apertures for the cleaner to revolve in, there being a section of cleaner at each section of the chimney; the chimney having a revolving reel or draught-regulator above, and a radiator below.

A represents the fire-place, intended to be built of brick or made of metal, and in which a cooking or parlor-stove can be placed, or any kind of a stove, to heat the upper part of a house.

B is a movable and adjustable radiator at the top of the fire-place, and is for the purpose of continuing the pipe from a stove through the centre aperture C, to carry off the smoke through the chimney D, and the heat from the stove is retained below, or carried up through the pipes E E, that may be attached and lead to any rooms or chambers above, so as to carry up the heat and heat the upper rooms.

When a cooking-stove is used, all the steam, smell, &c., of the cooking are carried off through the oblong

aperture F into the chimney D, the outside pipes, E E, having been closed. The soot that falls down the chimney can be cleaned out, by removing the radiator B, at any time, or can be taken out at the door G. The radiator, B, is a circular plate, with the two apertures, C and F, and rests upon a circular ledge at the lower part of the chimney, above the fire-place, and is inserted or removed at any time, by being taken out edgewise, through the slots J J of the ledge H. The body of the chimney is formed of cast-iron tubes, each about six feet in length, having a shoulder at each joint for the upper tube to rest in, and at each joint are cross-beams K, of bar-iron, permanently set into the shoulders of the tube, having a centre aperture, in which the central rod or pivots, L, of the square cleaners, M, operate and are guided. The rod L has a square joint above each cross-piece K, so as to revolve each section of the cleaners, M, at the same time.

N is the vane, at the top of the rod L, that revolves the cleaners M, according to the action of the wind, thus preventing soot from collecting against the sides of the chimney D. Near the top is a revolving reel or draught-regulator P, that is attached to the rod L, and revolves with the movement of the vane, having apertures at one side of the reel, opposite to the direction of the wind, to prevent the chimney from smoking, and regulate the draught.

The pipe-hole R is for the purpose of inserting a pipe into the chimney from a stove on the outside.

What I claim as my invention, and desire to secure by Letters Patent, is—

1. The combination of the self-acting cleaners M with the guides K, when constructed with and operated by means of the vane N, as herein described, and for the purpose set forth.

2. Also, an iron tubular chimney, in sections, with a fire-place A, radiator B, reel P, cleaners M, and vane N, when constructed, combined, and operated as herein described, and for the purposes set forth.

SAMUEL HOKE.
